(57) CLAIM

The ornamental design for a tumbler, as shown and described.

DESCRIPTION

FIG. 1 is a perspective view of a tumbler;

FIG. 2 is a right side elevation view thereof, the left side elevation view being a mirror image thereof;

FIG. 3 is a top plan view thereof;

FIG. 4 is a rear elevation view thereof;

FIG. 5 is a bottom plan view thereof;

FIG. 6 is a front elevation view thereof; and,

FIG. 7 is a perspective view thereof, shown with an environmental lid for clarity of disclosure.

The portions of the tumbler shown in broken line form no part of the claimed design. The broken lines immediately adjacent the solid line in FIGS. 1 and 3 depict the bounds of the claim and form no part thereof. The broken line showing of a lid in FIG. 7 depicts environment and forms no part of the claimed design.

1 Claim, 5 Drawing Sheets
